US0D1047700S

(12) **United States Design Patent** (10) **Patent No.:** **US D1,047,700 S**
(45) **Date of Patent:** **** Oct. 22, 2024**

(54) **PACKAGING**

- (71) Applicant: **Regeneron Pharmaceuticals, Inc.**,
Tarrytown, NY (US)
- (72) Inventors: **Andrew Cook**, Troy, NY (US); **Victor Bradford**, Troy, NY (US); **Jason Smith**, Latham, NY (US); **Sibgat Ulla**, Rensselaer, NY (US)
- (73) Assignee: **Regeneron Pharmaceuticals, Inc.**,
Tarrytown, NY (US)

(**) Term: **15 Years**

(21) Appl. No.: **29/851,364**

(22) Filed: **Aug. 26, 2022**

(51) LOC (14) Cl. **09-03**

(52) U.S. Cl.

USPC **D9/424; D9/737**

(58) **Field of Classification Search**

CLAIM

The ornamental design for packaging, as shown and described.

DESCRIPTION

FIG. 1 is a bottom, rear, right perspective view of packaging showing our new design;

FIG. 2 is a bottom, rear, left perspective view thereof;

FIG. 3 is a rear elevation view thereof;

FIG. 4 is a front elevation view thereof;

FIG. 5 is a left side view thereof;

FIG. 6 is a right side view thereof;

FIG. 7 is a bottom plan view thereof; and,

FIG. 8 is a top view thereof.

The broken lines of even length shown in the drawings illustrate portions of the packaging that form no part of the claimed design.

1 Claim, 5 Drawing Sheets
